ATTACHING DEVICE FOR CUTTING SURGICAL ADHESIVE TAPE ON SPOOLS

Filed April 1, 1927

FIG. 1.

FIG. 2.

FIG. 3.

Harry M. Kirkham Inventor
By Loyall J. Miller, Attorney

Patented May 29, 1928.

1,671,904

UNITED STATES PATENT OFFICE.

HARRY M. KIRKHAM, OF KANSAS CITY, MISSOURI.

ATTACHING DEVICE FOR CUTTING SURGICAL ADHESIVE TAPE ON SPOOLS.

Application filed April 1, 1927. Serial No. 180,143.

My invention relates to improvements to cutters for adhesive tape, and the like, on rolls.

The object of my invention is to produce a device of the character described which will be new, useful and practical, compact, strong and efficient for the purposes intended; that will be cheap in construction and manufacture and easily handled and used; and be of utility.

It is known to those familiar with the art to which my invention pertains that surgical adhesive tape is made of heavy cloth and filled with a heavy adhesive filler and adheres very tenaciously to the layer next below the portion desired to be cut when placed in a roll on a spool; it is also hard to handle after being cut and removed from the spool owing to its liability to touch and therefore to become adhered to the shears cutting it or the other part of the tape or to the hands, or other object which it may contact. It is also a very slow process and unhandy in handling the roll of surgeons' adhesive tape with the hands to unroll it and cut it with shears.

One of the needs of surgeons is a cheap easily attachable and detachable device for attaching to the spool containing surgeons' adhesive tape which will be strong properly proportioned and practical in the cutting of the tape from the spool as desired.

With these and other objects in view the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit and principle or sacrificing the advantages of the invention. The novelty, invention, and other objects will be more fully shown in the specification, claims and accompanying one sheet drawing, of which,

Figure 1 is a perspective view of the device attached to a roll of adhesive tape showing a part of the device in dotted-in portions; Fig. 2 is a perspective view of the device showing the cutting edge ground on the blade member; Fig. 3 is an alternate form of the cutting blade or detached cutting edge attached to the blade member.

Like characters or references designate like parts in all the figures.

One embodiment for accomplishing the purpose of my invention is as follows:

I provide a handle member 1, having arms 2, 3, with coiled spring ends 4, 5, adapted to fit into the spool cylinder 6 of an ordinary tape spool having protecting side discs 7, 8, said arms 2, 3, have a horizontal portion 9 therebetween; I also provide a cutting member 10 having integral therewith at its upper end a sleeve 11, adapted to fit over said portion 9, and having a portion 12 preferably convexed between said sleeve portion and the cutting blade portion 13, thereof. Said cutting blade portion is beveled from 14 to the cutting point 15. I also provide the detached blade member 16 with perforations therethrough 17, 18, adapted to be held in place by screws 19, 20, to said cutting member 10 through perforations near its lower edge. Said detached and attached cutting blade member has beveled edge between surface 21 and outer cutting surface 22 similar to the beveled edges 14, 15, of said first described blade member.

It is my desire to have the cutting member and blade member of such width as will be suitable to be used on various widths of adhesive tape and the like to be cut off so such widths will not interfere with the easy turning of the roll of adhesive tape and the device between the outer disc 7, 8.

In operating, the arms 2, 3, are slightly sprung apart to go down over the outer surfaces of discs 7, 8, and coil springs 4, 5, are adapted to be inserted in the outer respective ends of the spool cylinder 6 around which the tape 2, 3, is rolled. When it is desired to cut a piece of tape, the operator pulls the outer end 24 of the roll of tape 23 forward of said blade member 13 sufficiently to have the size of tape desired rolled out beyond the cutting blade. As soon as this is done he pushes downwardly on the surface of convex portion 12 of cutting member 10 so as to cause the cutting surface 15 of the cutting blade to be firmly against the tape at point 25. Holding the cutting member firmly he then quickly pulls up on one side edge of the unrolled tape following the pressure across the tape thereby cutting it from side to side and giving him the desired sized piece of tape. It is to be understood that the cutting member 10 shall

be of sufficient strength and thickness for the purpose of cutting the various strengths and thicknesses of tape desired to be used.

From the description and accompanying 5 one sheet drawing; the specification, and appended claims, the advantages of construction, application, manufacture and operation will be apparent to those skilled in the art to which my invention pertains. I 10 have entered into a detailed description of the construction, the arrangement of the parts and preferred embodiment of my invention, to impart a full and exact understanding of said embodiment. I do not desire, however, to be understood as confining myself to the specific construction and relative arrangement of parts inasmuch as in the future practice of the invention various 15 changes and modifications may be made 20 such as fall within the scope of my invention as defined in my appended claims.

Having thus described the invention what is claimed and desired to be secured by Letters Patent, is:

25 1. A device of the character described, comprising a wire member having a straight horizontal section and two arms at right angles thereto, each of said arms having an inwardly coiled portion at its outer end

adapted to be inserted in and movably fit 30 in the inside of the end of a spool for holding adhesive tape, and the like; a metallic convexed member having an integral sleeve at one end adapted to movably fit said straight horizontal section of said wire 35 member, and having at the other end a sharp cutting surface adapted to cut adhesive tape and the like.

2. The combination with a spool of adhesive tape, and the like, of a device of the 40 character described, comprising a wire member having a straight horizontal section and two arms at right angles thereto, each of said arms having an inwardly coiled portion at its outer end; a metallic convexed 45 member having an integral sleeve at one end and a sharp cutting surface at the other; said coiled portions being adapted to movably fit in the inside of the ends of said spool, said sleeve being adapted to movably fit said horizontal section of said wire member, said convexed member being adapted to movably fit inside the discs of said spool, and said cutting surface being adapted to cut adhesive tape and the like while on 5 said spool.

HARRY M. KIRKHAM.
